METAL CRIBBING.

Otto S. Flath, Chicago, Ill.

Application September 18, 1944, Serial No. 554,697

4 Claims. (Cl. 61—47)

My invention relates to cribbing composed of sheet metal members or elements for constructing walls for supporting embankments or "fills," with all of the elements composed of preformed elongated rectangular sheets of such formation or shape as to provide for great economy in manufacture, being of comparatively simple construction, which may be readily assembled at the place of use and the respective members secured together without need of special tools or skill. The respective members are of such construction that they may be easily handled and quickly assembled, thus especially adapting my improved members or units for use in the construction of walls for trenches and the like where time is of the essence.

The invention, more specifically stated, contemplates the provision of a pair of uniform units constituting, respectively, headers and stretchers whose ends are so formed that they may be readily secured together into superposed courses capable of withstanding the accumulated compressive loads to which the cribbing structure may be subjected; with the ends of the respective members arranged to be rigidly secured together without the need of special fastening elements and the elements of one course adapted to be secured to a pair of elements or units of two superposed courses; the headers and stretchers being so formed as to provide an uninterrupted or unbroken outer face or wall and thus eliminating the use of separate filler elements, as, however, is the case with many forms of cribbing heretofore designed.

The foregoing objects and advantages, as well as other advantages inherent in the invention, will all be readily apparent from the following detailed description of the accompanying drawing wherein:

The figure is a perspective view of a portion of the cribbing as viewed from the interior; with only a portion or the contiguous ends of superposed headers and of superposed stretchers being shown.

In the particular exemplification of the invention, the cribbing is composed of two sets of units, with the units of each set made of uniform construction and one set constituting the headers 10 each formed of a single elongated rectangular metal sheet of predetermined length and width; with the main or body portion provided with rigidifying surfaces in the form of one or more longitudinally extending corrugations or laterally bowed portions 11, which terminate a short distance from the ends of the sheets

as shown; while the longitudinal marginal portions above and below the rigidifying surfaces 11 are straight and disposed in the same vertical plane so that the longitudinal edges of the respective headers may be in continuous abutting relation to provide a complete closure between the headers.

The plane ends of the headers are bent at right angles to the body portion, as shown at 12, with both ends preferably bent toward the same side of the sheet and the bent ends preferably provided with uniformly spaced holes 13. It will be understood that both ends of the headers are of similar construction permitting the headers to be used end for end, so that the illustration and description of one end will suffice.

In the exemplification, the body portion of the header, for example the bowed portion 11, is shown provided with a bolt-receiving hole 14 preferably arranged at the longitudinal median line. Where the retaining wall or cribbing is to be of some length, a second set of headers 10 may be arranged in back-to-back or flush parallel relation and the headers of the two sets bolted together and thus provide a rigid two-piece unit or header 10 with the bent ends 12 at the same end of the composite or two-piece header disposed in opposite directions. It will be understood that the holes 14 are adapted to receive suitable bolts whereby the back-to-back headers may be firmly clamped together when the nuts are screwed up tightly on the bolts.

The stretchers 15, which may be of the same length as the headers 10, or of any desired length, are also of sheet metal and given channel form with relatively wide rigidifying surfaces or longitudinal flanges 16 at their upper and lower edges. The stretchers in the different courses preferably are arranged with their flanges 16 disposed inwardly, with the flanges of the stretchers in continuous flush relation thereby providing the outer face of the cribbing with an uninterrupted or imperforate surface, which also permits the bent ends 12 of the headers to extend in flush relation or contact with the outer sides of the stretchers as shown in the drawing. The stretchers adjacent their ends are provided with uniformly spaced bolt receiving holes adapted to register with the holes 13 in the flanged or bent ends 12 of the headers in order to receive the bolts 17; and the ends of the stretchers preferably are arranged in abutting relation with the sides of the headers.

In order to maintain the superposed relation of the stretchers, especially when the latter are of

some length, I prefer to provide the flanges or sides 16 of the stretchers at uniform spaced intervals apart with bolt-holes 18 for receiving the small bolts 19. With the flanges or sides 16 extending throughout the length of the stretchers and the flanges or sides 16 of the superposed stretchers bolted together, a very rigid cribbing is provided adapted to withstand the lateral strains and pressures of the "fill."

In the cribbing construction shown, the stretchers 15 are arranged in staggered relation with respect to the courses of the headers 10 so that each stretcher 15 is in abutting relation with a pair of superposed headers and the ends of the stretchers secured to the respective headers by means of the bolts 17. As the bolt-holes in the bent ends 12 of the headers and those in the ends of the stretchers are all of uniform spacing it is apparent that this staggered arrangement may be made and the respective courses secured together against independent shifting movement; while other courses for longitudinally extending the cribbing may all be tied together by placing the additional headers in back-to-back relation with the headers shown so their flanges or ends 12 are disposed in a direction opposite to those shown and then bolting the back-to-back headers together by employing the bolt-holes 14. With this arrangement all courses of the cribbing will be firmly secured together and a continuous non-shifting rigid structure provided. It will be understood that the inner ends of the headers also are provided with similar stretchers thereby providing a cribbing with a plurality of rectangular pockets or chambers for receiving the "fill," thereby securely anchoring the cribbing against outward or shifting movement.

With the headers and stretchers, each of uniform formation, and formed from plane rectangular sheets of metal, the cost of manufacture is materially less than the cost of cribbing as heretofore constructed, while at the same time assembly or construction of my improved cribbing may be more readily accomplished without need of special skill or tools as the two units, namely headers and stretchers, are each of uniform construction throughout thus enabling end for end use of the units without need of matching the respective units as, however, is required in structures heretofore in use.

My present application is a continuation in part of my copending application Serial Number 460,023, which issued Sept. 19, 1944, Patent No. 2,358,698.

What I claim is:

1. A cribbing composed of two sets of elongated rectangular metal sheets, each set consisting of uniform members, one set of members constituting headers provided with straight longitudinal marginal portions and arranged in superposed relation with the longitudinal edges of the sheets of one course resting on the longitudinal edges of the sheets in the subjacent course, the ends of said header members being bent laterally toward the same side of the header and provided with uniformly spaced bolt-holes; the other set of

members constituting stretchers with their longitudinal marginal portions at top and bottom bent laterally toward the same sides of the stretchers to provide stretchers of channel form arranged in superposed relation with the longitudinal portion of one stretcher resting on the longitudinal portion of the subjacent stretcher and the marginal portions all disposed inwardly and the stretcher ends arranged rearwardly of the bent ends of the headers and bolted thereto.

2. A cribbing composed of two sets of elongated rectangular metal sheets, one set consisting of sheets provided with longitudinally extending bowed portions extending toward the same side of the sheets and with laterally bent ends disposed toward the same side of the sheet to constitute headers; while the other set consists of sheets bent into channel form with the channel sides disposed inwardly so as to provide the cribbing with a continuous uninterrupted outer face, the ends of the stretchers being arranged rearwardly of the laterally bent ends of the headers and the ends of the headers and stretchers provided with uniformly spaced bolt-holes; and bolts whereby the headers and stretchers are removably secured together.

3. A cribbing composed of elongated rectangular metal sheets with their ends uniformly bent at right angles toward the same sides of the sheets and provided with uniformly spaced bolt-holes, said sheets having straight longitudinal edges and arranged in superposed edge-to-edge relation to constitute headers; and elongated straight sided channels arranged in superposed relation with the sides of the channels resting on each other and disposed inwardly and provided with bolt-holes, while the ends of the channels have uniformly spaced bolt-holes and arranged rearward of the bent ends of the headers and constitute stretchers, with the ends of each header arranged in overlapping relation with the ends of two superposed stretchers; bolts whereby the ends of the headers and stretchers are removably secured together, and bolts whereby the flanged edges of the superposed stretchers are removably secured together.

4. A cribbing composed of a pair of rectangular sheet metal units, the metal sheets of one unit being provided intermediate the longitudinal edges and the ends with longitudinally disposed rigidifying surfaces while the ends are bent laterally, said rigidifying surfaces and bent ends being disposed toward the same side; while the metal sheets of the other unit are pressed into uniform channel form with the longitudinal flanges or sides extending from end to end; the bent ends of the first mentioned unit and the main body portions of the second mentioned unit being provided with uniformly spaced holes adapted to register with each other when the sheets of the respective units are arranged in edgewise superposed relation; and fastening bolts arranged in the registered holes to hold the units in header and stretchers providing relation.

OTTO S. FLATH.
